CLAIM

The ornamental design for pad to be placed on a chair to prevent a child from slipping off, as shown.

DESCRIPTION

FIG. 1 is a front elevational view of a pad to be placed on a chair to prevent a child from slipping off, showing our new design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.
